UNITED STATES PATENT OFFICE.

ALBERT SWINDLEHURST, OF MONTREAL, CANADA, ASSIGNOR TO THE OLIVER TYPEWRITER COMPANY, OF CHICAGO, ILLINOIS, A CORPORATION OF ILLINOIS.

PAPER-GUIDE FOR TYPE-WRITERS.

SPECIFICATION forming part of Letters Patent No. 726,591, dated April 28, 1903.

Application filed July 10, 1902. Serial No. 115,083. (No model.)

To all whom it may concern:

Be it known that I, ALBERT SWINDLEHURST, of Montreal, county of Hochelaga, in the Province of Quebec and Dominion of Canada, 5 have invented certain new and useful Improvements in Paper-Guides for Type-Writers; and I do hereby declare that the following is a full, clear, and exact description thereof, reference being had to the accompanying drawings, and to the letters of reference marked thereon, which form a part of this specification.

This invention relates to improvements in type-writing machines, and refers more specifically to guiding devices for guiding the advance edge of a sheet of paper upon the platen as it approaches the striking-point of the type-heads and for holding the same properly engaged with the platen at the time it receives 20 the impression of the types.

My improvements are herein shown as applied to an Oliver type-writing machine of the general construction shown and described in the prior patent to Thomas Oliver, No. 25 599,863, granted March 1, 1898; but said improvements may be applied to machines of other kinds to which they may be adapted.

As shown in the drawings, Figure 1 is a perspective view of the type-bar-supporting frames of an Oliver type-writing machine, showing the standards by which they are supported from the machine, a part of the carriage, and a portion of the carriage-shifting frame. Fig. 2 is a cross-section taken through 30 the carriage and platen, presser-rollers, and paper-guides and showing also a portion of the shifting-frame. Fig. 3 is a perspective view of one of the paper-guides embodying my invention removed from the machine.

As shown in the drawings, A designates the 40 rotative platen, the shaft *a* of which extends through and has rotative engagement with end plates B B of the carriage-frame. Said platen-shaft is provided at one end with a 45 turning-knob A'.

CC designates U-shaped type-bars, of which there are two sets, one located on each side of the striking-point of the types. But one bar of each set is herein shown. Said type-bars

are supported on a frame consisting of an angular bottom frame D, to which said type-bars are pivoted, a loop-frame D', rising from said frame D, and an oblique support D², against which the type-bars rest when thrown backwardly from the platen. Said type-bar frames are supported on the upper ends of standards E, which rise from the base E' of the machine.

F designates a portion of the carriage-shifting frame, and F' the front rail thereof, on which the carriage travels during the operation of printing.

G designates the forward horizontal longitudinal bar of the carriage, on the rear margin of which is formed the rack-bar, which constitutes a part of the letter-spacing mechanism of the machine. Said bar G is provided with rollers G', which rest and roll upon the bar F of the shifting-frame.

H H' H² designate presser-rollers located 70 beneath and in front of the platen, between which and the platen the advance edge of a sheet of paper is guided as it is inserted into the machine and which act to press and hold the paper against the platen. Said rollers are 75 supported in the machine-frame in the same manner as shown in the said Oliver patent hereinbefore referred to. As these features of the construction constitute no part of the present invention, they need not be more 80 fully herein described. A strip I, marked with a scale, is mounted on the upper free ends of the supporting-arms h of the upper front rollers H². Said strip is loosely connected at its ends with said arms, so that the 85 free margin thereof may adjust itself with respect to the platen.

J designates the lower guide-plate, which is attached at its ends to the end plates of the carriage-frame in rear of the platen and inclines downwardly and forwardly to direct the entering margin of the sheet of paper between the platen and lower rear presser-roller H.

K designates an upper guide-plate located 95 above the plate J and connected at its ends with the end plates B of the carriage. Said plate K is located in position to receive the advance edge of the paper as it passes from

the platen to guide said paper away therefrom and to prevent it from re-entering the space between the platen and the advance presser-roller H.

5 The foregoing parts of the machine are similar to the construction shown in the prior patent to Oliver, hereinbefore referred to, and only such parts of the machine are illustrated as are necessary to an understanding of the 10 application of my present improvements to said machine.

Referring now to the improvements constituting my invention, they are constructed as follows: L L designate two curved guide- 15 plates located between the carriage-platen and the type-bar-supporting frames D, between which and the platen the advance edge of a sheet or sheets of paper pass as the same reaches the top of the platen or the striking- 20 point of the types, said plates acting to hold the paper in close contact with the platen during the operation of printing. Said guide-plates L are curved at their rear parts to conform to the curvature of the platen. At their 25 adjacent ends the said plates preferably extend toward each other slightly beyond the supporting-frame for the type-bars and at their outer ends reach nearly to the ends of the platen. Said guide-plates L may be sup- 30 ported in any suitable manner over the platen by means holding the plates longitudinally immovable with respect to the carriage, so that the platen will move backwardly and forwardly beneath the guide-plates. As here- 35 in shown, said plates are mounted on vertical standards or posts M, which are attached at their lower ends to the part F of the shifting-frame, said standards being provided with integral horizontal lugs or projections M', 40 which extend beneath said part F of the shifting-frame and are rigidly affixed thereto. Said standards extend upwardly in front of the platen, one adjacent to each of the standards E, which support the type-bar frames. 45 In order to provide means for permitting movement of the guide-plates toward and from the surface of the platen in order that uniform pressure of the guide-plates on the 50 paper may be maintained when a greater or less number of sheets of paper are used, as in duplicating by carbon-paper and under other circumstances, the guide-plates have vertically-movable connection with the supporting-standards M. In the particular construc- 55 tion illustrated the guide-plates L are connected with said standards M by means of integral shanks L', which are bent downwardly from the forward margins of said guide-plates and have sliding connection with the 60 standards. As herein shown, said standards are provided with loops m', which are secured to the same and through which the shanks L' of the guide-plates extend in the manner shown in Fig. 3. This construction affords 65 vertically-sliding connection of the guide-plate shanks with the standards and permits

1 said guide-plates to be shifted upwardly and downwardly with respect to their supporting-standards to admit the passage of paper of varying thicknesses or a greater or less number of sheets of paper between the same and the platen. 7c

Means are provided for yieldingly holding the guide-plates L in contact with the platen or a sheet of paper passing between the same and the platen, so that said plates will automatically accommodate themselves to papers of varying thicknesses or varying numbers of sheets of paper. As herein shown, such yielding connection is afforded by means of 80 springs L², so applied as to act downwardly on the guide-plates, said springs preferably having the form of spiral contractile springs, one end of each of which is attached to a hook l on the shank L' and the other end to a similar hook m² on the standard or post. In assembling the parts the springs L² will usually be placed under tension, so that said plates will bear with a slight degree of pressure 85 against the platen. 90

The inner or adjacent ends of the guide-plates L are provided with upwardly-curved lips l', which act in the endwise movement of the platen to guide the side margin of a sheet of paper between the guide-plate and the 95 platen in the event of a sheet of paper or envelop being used which is so narrow that one or both of its side margins pass beyond or inside of the inner end of one of the guide-plates when the platen reaches either limit 100 of its endwise movement. Said upwardly-curved lips stand inside of the inner end margins of the plates, so as to engage the margin of the paper in advance of the end margins proper of the guide-plates, and thus insure 105 the entrance of the paper between the plates and platen.

It will be noted that in the construction described, wherein the guide-plates are attached to the shifting-frame, said plates move backwardly and forwardly with the carriage, and therefore maintain their lateral position relative to the platen. 110

The yielding connection of the guide-plates with the parts which support the same is of 115 considerable importance, for the reason that thereby a substantially uniform pressure is exerted upon the paper at the top of the platen notwithstanding variations in the thickness of the paper or the number of sheets used, as in making a number of carbon copies. Obviously if the plates be immovable toward 120 and from the platen the pressure on papers of varying thicknesses would be unequal and if suitable for a thin paper would afford an 125 objectionable resistance to the passage between the platen and the guide-plates of thick sheets or too great a number of sheets. So far as the advantage arising from the use of yieldingly-supported guide-plates is concerned, it 130 is obvious that the plates may be otherwise supported upon the machine-frame—as, for

instance, on the lower side of the type-bar frames, as in my prior patent, No. 691,503, dated January 21, 1902.

I claim as my invention—

5. 1. In a type-writing machine, the combination with the carriage-shifting frame, the carriage and platen, of type-bar-supporting frames located above the platen, and guide-plates located between the said type-bar frames and the platen, said guide-plates being connected with and supported by the shifting-frame.
10. 2. In a type-writing machine, the combination with a carriage-shifting frame, a carriage and platen, of type-bar-supporting frames located above the platen and guide-plates located between the type-bar frames and the platen, and means for movably supporting said guide-plates on the shifting-frame, affording movement of said guide-plates toward and from the platen.
15. 3. In a type-writing machine, the combination with a carriage-shifting frame, a carriage movable longitudinally thereon, and type-bar-supporting frames located above the platen, of guide-plates located between the type-bar frames and platen, and means for supporting said plates, affording movement thereof toward and from the platen.
20. 4. In a type-writing machine, the combination with a carriage-shifting frame, a carriage and platen, of type-supporting frames located above the platen and guide-plates for holding the paper against the platen, said platen being located between the type-bar frames and the platen at either side of the printing-point and means for movably supporting said guide-plates on the shifting-frame, constructed to hold the same yieldingly against
25. 5. In a type-writing machine, the combination with the shifting-frame, and a carriage longitudinally movable thereon and provided with a platen, of guide-plates located above

said platen and supported on said shifting-frame, and yielding connections between said plates and the frame affording downward pressure of the plates upon the platen.

45. 6. In a type-writing machine the combination with the shifting-frame and a longitudinally-movable carriage thereon provided with a platen, a type-bar-supporting frame located above the platen, guide-plates located between said platen and the shifting-frame, shanks on said guide-plates and standards attached to the shifting-frame with which the said shanks have endwise sliding engagement.

50. 7. In a type-writing machine, the combination with the shifting-frame and a longitudinally-movable carriage thereon provided with a platen, of guide-plates located above said platen, and provided with downturned shanks, standards affixed to said shifting-frame with which said shanks have longitudinal sliding engagement, and spring connections between said shanks and standards producing downward pressure of the guide-plates on the platen.

55. 8. In a type-writing machine, the combination with the shifting-frame and a longitudinally-movable carriage thereon provided with a platen, of guide-plates thereon located above the platen and provided with downwardly-projecting shanks, vertical standards attached to the shifting-frame and provided with loops through which extend the shanks of said plates, and springs connecting said standards with the shanks whereby said plates are held yieldingly against the platen.

60. In testimony that I claim the foregoing as my invention I affix my signature, in presence of two witnesses, this 27th day of June, A. D. 1902.

ALBERT SWINDLEHURST.
